UNITED STATES PATENT OFFICE.

WILLIAM GARRETT, OF BEAVER FALLS, PENNSYLVANIA.

MANUFACTURE OF SPLIT BLANKS.

SPECIFICATION forming part of Letters Patent No. 297,593, dated April 29, 1884.

Application filed October 19, 1883. (No model.)

To all whom it may concern:

Be it known that I, WILLIAM GARRETT, a citizen of the United States, residing at Beaver Falls, county of Beaver, State of Pennsylvania, have invented or discovered a new and useful Improvement in the Manufacture of Split Blanks; and I do hereby declare the following to be a full, clear, concise, and exact description thereof, reference being had to the accompanying drawings, making a part of this specification, in which—like letters indicating like parts—

Figure 1 is a diagram illustrating by a series of end elevations of a bloom the several changes of form undergone by the same in its manufacture under my invention, into a blank which is split or divided on one side; Fig. 2, a diagram similarly illustrating the manufacture of a blank split or divided upon two opposite sides; Fig. 3, a diagram showing the production of a rod or cylinder divided as in Fig. 2; and Fig. 4, ends view of blooms which are split or divided longitudinally under a hammer by a cutter.

My invention is designed for the manufacture of metal blanks, bars, or rods having a split or division extending inwardly from one side or from two opposite sides, said blanks being suitable and desirable to be worked into shovels, split keys, or coppers, &c.

To this end my improvements consist in a certain novel method of recessing and reducing a bloom to form a split blank, and in a blank having one or more lateral splits or divisions and formed from a bloom by the recessing and reduction in thickness thereof, as hereinafter more fully set forth.

In the practice of my invention I take a bloom, A, preferably of rectangular section, and, after having properly heated the same, indent or impress therein one or more lateral gaps or recesses, a, the depth of which corresponds with the depth of the split or division desired in the finished blank. I then reduce the blank by any suitable means to the thickness required, and in the operation close together the sides of the recess or recesses after the same have cooled below a welding-heat, such closed recess or recesses thus forming the desired lateral division or divisions.

The operation may be conveniently con-

ducted by the employment of rolls in the recessing and reduction of the bloom. In such case, and referring first to the manufacture of a blank having but one lateral split or division, I pass a bloom, as A, Fig. 1, between a pair of rolls, the lower of which is cylindrical, and the upper provided with a collar adapted to form a lateral recess or gap, a, in the bloom, producing the section A'. The bloom is again passed through the rolls, to reduce the recess a to the depth desired for the split of the finished blank, the section on each side of the recess being left intact, and the bloom being brought to the form shown at A''. The bloom is now turned over and passed between a pair of plain-surfaced rolls, the action of which is exerted parallel with the recess a, by which the entire section is reduced perpendicularly to said recess, as also the width, but not the depth, of the recess, as shown at A''. This operation is continued by successive passes between the plain-surfaced rolls, as in the ordinary method of rolling, the faces of the recess a being closed together in the course of the operation, as at A³, and the bloom being continuously reduced in thickness, as at A⁴, A⁵, A⁶, and A⁷, until a blank, A⁸, of the desired thickness and having a lateral split or division, a', between the closed up sides of the recess a, is produced. Such blank, which may be made of any proper width and thickness, is in condition to be cut into desired lengths for the manufacture of various articles. It is to be observed that the closing of the recess will not cause the welding together of its sides, as the bloom is at this stage of the operation below a welding-heat.

The manufacture of a blank which is solid at and adjacent to its center and split or divided on two opposite sides is conducted in a similar manner, as illustrated in Fig. 2. The heated bloom A is first passed between a pair of rolls provided with collars of such form and location as to form two recesses or gaps, a a, on opposite sides of the bloom, producing a section, as shown at A¹⁰. The bloom is then passed once or more through the rolls, whereby the depth of the recesses a a is first increased, as at A¹¹, and finally brought to the limit required, as at A¹². The bloom is then placed in an ordinary open square groove, or

by any other means known to the trade brought to the desired section, as shown at A¹⁴, after which it is rolled flat parallel with said recesses in the ordinary method of rolling until 5 reduced, as shown, to a finished blank, A¹⁵, of the required thickness, and provided with a lateral split or division, a', on each of two opposite sides. The bloom A (shown in Fig. 3) is similarly recessed, and reduced, as at A¹⁶, 10 A¹⁷, A¹⁸, A¹⁹, and A²⁰, and the resultant blank thereafter rolled in the ordinary way into a cylindrical bar or rod, A, having two opposite splits or divisions, a.

In lieu of forming the recess or recesses a by rolling, as before described, the same 15 may be made by heating a bloom, placing it under a hammer, and partially splitting or dividing it by means of a cutter, producing sections, as indicated in Fig. 4, the recess or recesses a of which are afterward closed together when the bloom is below a welding-heat under the ordinary process of rolling or hammering.

I claim herein as my invention—

1. The improvement in the art of manufacturing laterally split or divided blanks which 25 consists in indenting or impressing in a suitably rolled and heated bloom one or more lateral gaps or recesses along the entire length thereof, and thereafter reducing the bloom to 30 the required thickness, and simultaneously closing up the recesses thereof without welding the same, substantially as set forth.

2. The improvement in the art of manufacturing laterally split or divided metallic blanks 35 which consists in first rolling one or more lateral gaps or recesses in a bloom, and thereafter closing up said recesses and reducing the bloom to the required thickness by rolling the same parallel with the recesses thereof, 40 substantially as set forth.

In testimony whereof I have hereunto set my hand.

WILLIAM GARRETT.
